EVAPORATIVE COOLER

Richard N. Brookins, South Gate, Calif., assignor
to Essick Manufacturing Company, Los Angeles, Calif., a corporation of California

Application February 10, 1948, Serial No. 7,371

9 Claims. (Cl. 261—97)

1

This invention relates to an evaporative cooler and it is more specifically concerned with features of construction pertinent to such a device and particularly to the casing or housing of such a device, it being a general object of the present invention to provide an evaporative cooler having or involving a casing construction which is exceedingly simple and inexpensive of manufacture and is at the same time such as to house the elements of the cooler such as the air circulating means, evaporative pads, water circulating equipment, etc. in a most compact and advantageous manner.

Evaporative coolers are characterized, generally, by a box-like casing or housing in which the working parts are located, the working parts including mainly filter pads, a water distributing system for wetting the pads, air circulating means, controls, etc. The case of the ordinary evaporative cooler is ordinarily formed of sheet metal and heretofore such structures have involved numerous parts or sections requiring assembly and necessitating the use of numerous fastening devices.

It is an object of the present invention to provide a casing for an evaporative cooler involving or including but two unitary sections each of which is essentially L-shaped in configuration and which, when combined, form the essential parts of the case.

Another object of the invention is to provide a case of the general character referred to wherein one of the two sections carries or has joined with it retainers so that when the two sections are joined together the entire structure forms a complete case around the working parts of the cooler, such as the air circulating means, evaporative pads, etc.

A further object of the present invention is to provide a casing construction of the general character referred to in which the two sections are such as to spring or lap together making it unnecessary to employ screws, catches, hooks, or other fasteners such as are commonly employed in connection with casings, or housings wherein parts are relatively movable.

It is a further object of the present invention to provide a construction of the general character referred to wherein parts of the apparatus are included in or carried by one section while other parts are carried by or included in the other section, and means is provided to connect the parts in the two sections preliminary to final assembly so that when the sections are fully assembled the parts within the sections are connected for proper operation.

2

It is another general object of the present invention to provide a construction of the general character referred to involving a minimum number of simple, easily formed parts all of which afford a compact, smooth simplified structure that is inexpensive of manufacture and exceptionally simple and easy to handle.

The various objects and features of my invention will be fully understood from the following detailed description of a typical preferred form and application of my invention, throughout which description reference is made to the accompanying drawings, in which:

Fig. 1 is a perspective view illustrating a structure embodying the present invention. Fig. 2 is an enlarged vertical sectional view of the structure being taken as indicated by line 2—2 on Fig. 1. Fig. 3 is an enlarged detailed sectional view of a portion of the structure shown in Fig. 2, being a view taken at the upper rear corner of the structure. Fig. 4 is an enlarged detailed sectional view of a portion of the structure shown in Fig. 2, being a view taken at the lower rear corner of the structure. Fig. 5 is a plan section taken at one corner of the structure, being a view taken generally as indicated by line 5—5 on Fig. 2. Fig. 6 is a vertical sectional view of the structure taken as indicated by line 6—6 on Fig. 2. Fig. 7 is an enlarged plan section taken as indicated by line 7—7 on Fig. 6, and Fig. 8 is a perspective view similar to Fig. 1, illustrating the two main sections of the structure separated and in position ready to be assembled.

The structure embodying the present invention includes, generally, a case made up of two unitary sections, one a main section A and the other a back section B. The structure further includes side sections C, preferably joined to and carried by one of the first mentioned sections. In the case illustrated the side sections are joined to and make a part of the back section B. The structure further includes retainers joining or coupling the sections A and B and in the preferred form of the invention there is a retainer D where the rear end of the bottom section joins the lower end of the back section and a retainer E where the upper end of the front section joins the forward end of the back section. It is also preferred that the construction include retainers F holding the lower forward portions of the side sections C. In the construction including the present invention there is an air circulating means G, preferably a motor driven fan, a water supply line H entering the structure to supply water thereto, control means J and K

for the means G and the supply line H, respectively, a plurality of evaporative elements L, holders M for the elements L, a water distributing system N coupled with the supply line H through the control K and operable to supply water to the elements L, and a support O for the elements B and C.

The case sections A and B are unitary elements built up of sheet metal, and in accordance with the invention each of the sections is generally L-shaped in form, the main section A being formed essentially of a front 10 and a bottom 11 while the back section B is formed essentially of a top 12 and a back 13. The sections A and B combined with the retainers D and E, form a construction which is assembled into the form shown in Figs. 1 and 2 of the drawings wherein the sections are held together, establishing a casing construction suitable for carrying the various other elements of the apparatus. The casing sections A and B are so formed and related as to engage each other and remain in assembled condition without the use of fasteners of any form whatsoever except for the retainers D and E, all of which will be more specifically described.

The front 10 of the main section A may be a panel-like part, for instance, a flat vertically disposed sheet or plate such as is shown in the drawings, and is preferably formed with an opening 15 through which the air cooled by the evaporative action occurring within the structure discharges into a room or other area. It is to be understood, of course, that the front 10 may be varied widely from the form and construction illustrated in the drawings, as circumstances or fancy may dictate.

The bottom 11 of case section A may be a flat or substantially flat plate-like part horizontally disposed with its forward edge portion joined to the lower edge portion of the front 10 at a corner 16 which may be suitably curved.

The back section B is characterized by the top 12 and back 13, the rear edge portion of the top 12 being joined to the upper edge portion of the back 13 at a corner 17. When the sections A and B are assembled, as shown in Figs. 1, 2 and 6 of the drawings, the forward edge portion of top 12 adjoins the upper edge portion of front 10 while the lower edge portion of back 13 joins the rear edge portion of bottom 11. So far as the broader principles of the invention are concerned the form, shape or character of the parts 12 and 13 may vary widely. In the case illustrated the top 12 is shown as a flat plate-like part free of openings, whereas the back 13 is shown as a plate formed with a plurality of openings or air passages 18, the passages being formed by the provision of louvers 19 in the back in the manner common to structures of this general character.

The retainer D that occurs at the lower rear portion of the case where the rear edge of bottom 11 joins the lower edge of back 13 is preferably a simple upstanding or vertically disposed part 20 which may, in practice, be a flange-like part projecting upwardly from the bottom 11. The flange-like part 20 may be of considerable vertical extent in order to properly cooperate with other parts to establish the tray that will be hereinafter described, to carry the support O and also to carry the holder which serves to hold the element L located at the inner side of the back 13 as will be hereinafter described.

The retainer E at the upper edge of the front 10, where the forward edge of the top 12 joins the front 10, is preferably a rearwardly projecting

flange-like part 22 projecting from the front 10. It is preferred in practice that the flange-like part 22 be integrally joined with the front 10 while the flange part 20 is integrally joined with the bottom 11. The sections A and B are so formed and related that when the lower edge portion of the back 13 is engaged within or behind the flange 20 the forward edge portion on the top 12 can be engaged under or beneath the flange part 22 as shown in Fig. 2 of the drawings. The sections A and B, being formed of sheet metal, have sufficient inherent resilience to enable assembly or joinder of the sections at the position shown in Fig. 2 of the drawings. In practice it has been found desirable to so form the main section A as to have the front 10 thereof extend upwardly and slightly rearwardly from the forward edge portion of the bottom 11 when the section A is separated from section B so that when the section B is assembled with the section A the upper edge portion of the front 10 is deflected somewhat forwardly, with the result that it exerts a rearward pressure against the upper edge portion of the section B, thus maintaining the sections A and B in a snugly joined assembly.

In accordance with the preferred form of the present invention the main section A has its bottom 11 provided with upstanding side flanges 30 and with an upstanding front flange 31. The forward ends of flanges 30 are joined to the ends of flange 31 and the rear ends of flanges 30 are joined to the ends of the flange part 20, all with the result that the assembly of flanges combined with the flat bottom form an upwardly opening tray or basin that serves to catch water draining from the elements L or other parts of the structure, when the apparatus is in operation. In practice the bottom 11 and several flanges are integrally joined or formed of a single continuous sheet of metal, so that the basin is free of joints or connections subject to leakage. It is desirable to provide the bottom 11 with a drain opening and a suitable drain connection 33.

The front 10 of the section A is provided at its side edges with rearwardly projecting flange parts 34 and at its bottom edge with a rearwardly projecting flange 35. The upper ends of the side flanges 34 join with the ends of the flange 22 of retainer E while the lower ends of the side flanges 34 join with the ends of the bottom flange 35. Mounting or face flanges 36 project from the flanges 22, 34 and 35 in a common plane, somewhat to the rear of the plane of the front 10. The front 10, flanges 22, 34, 35, and several flanges 36 may be formed of one continuous or integral sheet of material.

With the front 10 and the bottom 11 formed as above described the forward edge portion of the bottom part 11, with its forward end flange 31, nests or seats in the corner formed by the bottom flange and the lower edge portion of the front 10, and these parts are preferably permanently secured together or integrally joined as by welding, or the like, and through such joinder or connection the section A is assembled as a permanent or unitary L-shaped structure.

The top 12 of section B is preferably a flat panel-like part with downwardly turned edge flanges 40 which join at the corners and which are preferably integral with the flat panel-like part of the top. The back 13 of section B is preferably provided at its upper end or edge with a forwardly projecting flange 41 which fits against the under side of the top 12, immediately inside of the flange 40, depending from the rear edge of the top. A forwardly projecting flange

42 projects from the lower edge of the back 13 to engage the support O provided at the rear of the structure. The flange 40 at the rear edge of top 12 overlaps or depends somewhat over the upper edge portion of the back 13 while the flange 41 seats against the lower side of the top 12. These parts are preferably joined by welding, or the like, so that the top and back are united into an integral or permanent unit.

The side sections C are preferably alike and are generally similar to the back 13 of section B. Each side section C includes a plate or panel-like part 45 with a plurality of openings established by the provision of louvers 46. The rear edge portion of each side section C is joined to the back 13 by a corner 41 and in practice the plates or panels 45 of the side section C may be integrally joined with the back 13, these parts being formed of one single continuous sheet of material bent into a generally U-shaped structure with vertically disposed parts forming the back of section B and the panels of the two side sections C. The forward edge portion of each side section C is provided with an inwardly turned or projecting flange 48 and in the particular form of the invention illustrated the flanges 48 of sections C cooperatively engage the retainers F. The plate of each side section C has an inwardly turned flange 49 at its lower edge to engage the support O.

The upper edge portions of the plates 45 of side sections C engage behind or within the flanges 40 depending from the top 12 and inwardly turned or horizontal flanges 50 are provided on the upper edges of the plates 45 similar to the flanges 41 on the back 13. The flanges 50 engage the under side of the top 12 and it is preferred that they be permanently joined to the top 13 as by welding, or the like. With the upper edge portion of the back 13 permanently joined to the rear edge portion of the top 12 and with the upper edge portions of the side sections C permanently joined with the edge portions of the top 12, the back section B and the side sections C form a rigid stable structure best illustrated in Fig. 8 of the drawings.

The support or supports O serve to support the section B from the section A, and when sections C are joined to section B the supports O support both the section B and the sections C. Each support O may be in the nature of an inwardly projecting flange 55 provided on an upstanding flange of the bottom 11. I show a flange 55 projecting inwardly from the flange 30 at each side of the bottom 11 and the flanges 49 and the lower edges of the side plates 45 rest on the flanges 55. There is a flange 55 projecting horizontally from the flange or retainer 20 at the rear edge of the bottom 11 and the flange 42 at the lower end or edge of the back 13 rests on this flange 55. When the section B with the sections C combined therewith is properly engaged with section A so that it is properly held by the flanges 20 and 22, the flange 42 rests on the supporting flange 55 at the rear of the structure, as shown in Fig. 2, while the flanges 49 rest on the supporting flanges 55 at the sides of the structure, as shown in Fig. 6.

The retainers F are provided to engage or hold the forward lower corners of the side sections C so that these parts of the side sections are held snugly against the inner sides of the side flanges 30 when the side sections are engaged with the supports. The retainers may be in the form of projections 60 projecting rearwardly

from the inner side of the front 10 to be engaged by the flanges 48 at the forward vertical edges of the plates 45. The projections 60 are spaced somewhat from the side flanges that project rearwardly from the vertical edges of the front 10 and the flanges 48 on the side sections C are such as to fit between the projections 60 and the side flanges projecting from the vertical edges of the front 10. The projections 60 may be inclined to extend downwardly and inwardly and the parts may be related and proportioned so that as the flanges 49 at the lower edges of the side sections move into position on the supports O the side sections are wedged or forced somewhat outwardly to bear snugly against the upper edge portions of the flanges 30 projecting upwardly from the bottom 11, thus providing a smooth fit between the lower edge portions of the side sections and the bottom 11 of section A.

The air circulator or circulating means G provided in the apparatus preferably involves a fan 65 driven by a motor 66 mounted on a stand 67 projecting upwardly from the bottom 11. The fan circulates air out through the opening 15 in the front 10 of section A, the air thus circulated being drawn in through the openings provided in the side sections C and the back 13. The control J provided for the means G preferably includes a suitable switch 68 in the power line 69 extending to the motor 66. The switch 68 is shown mounted at the rear side of the front 10 and an operating knob 70 for the motor is located at the front side of the front 10.

The evaporative element or cells L may, in practice, be of any suitable form or construction. They are shown as envelopes 71 carrying suitable material 71a such as excelsior, or the like, the envelopes being held in the holders M which, in practice, may be frame-like structures suitably supported at the inner sides of the back 13 and side panels 45. The holders M are shown supported from the flanges 42 and 49 by clips 12 and hold the excelsior filled envelopes over the openings in the back and side panels.

The water distributing system is shown as including distributor pipes 75 located immediately beneath the top 12 and over the elements L, the several pipes 75 having jet openings 76 that discharge water onto the cells L. The several pipes 75 are joined to a common header 77. The supply line H is shown entering the structure through the front 10 at one side thereof and the control means K includes a valve 80 controlling flow from the supply line and having an operating handle 81 at the front side of the front 10 of section A. A suitable fluid connection is provided between the valve 80 and the header 77. This connection involves, generally, a delivery pipe 82 extending from the valve 80 at the rear of the front 10, a receiving pipe 83 depending from the header 77 below the top 12, and a flexible connector 84 which joins the pipes 82 and 83. The flexible connector 84 is initially applied to one or the other of the pipes, as for instance, to the pipe 83 and as the sections A and B are being assembled and while the forward edge portion of the top 12 is spaced somewhat from the upper edge portion of the front 10, the operator reaches into the structure and applies the flexible connector 84 to the pipe 82.

From the foregoing description it will be apparent that I have provided a case which is formed essentially of the L-shaped sections A and B and that the side sections can be joined

to or carried by one or the other of the first mentioned sections. The two units are easily assembled or fitted together and, being formed of sheet metal, they possess sufficient yield or spring to allow for assembly into the position shown in Figs. 1 and 2 of the drawings, and when assembled they are firmly and securely joined, making it unnecessary to employ screws, hooks, or like fasteners. In the process of bringing the sections A and B together, the fluid connection is established, as above described, thus making the entire structure ready for operation. By suitably regulating the flow of water into the elements L and by operating the fan by means of the motor 66, the apparatus will serve as an evaporative cooler so that the air discharged through the opening in the front of section A is considerably cooler than that drawn in through the back and the sides. Through the present invention there are but few simple parts, the various essential parts of the case being formed of sheet metal and the structure is particularly desirable since it is free of fasteners such as screws or bolts likely to jar loose or to become fouled through oxidation, or the like. When it is desired to open the structure it is merely necessary to spring the front 10 forward from the upper edge portion of the top 12 freeing the section B so that it can be swung upwardly and rearwardly away from section A to be finally lifted away from section A, freeing the two sections in a manner such as is shown in Fig. 8 of the drawings.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A cooler case of the character described including, two separable unitary sections each generally L-shaped, one section being a main section including a lower horizontally disposed part forming the entire bottom of the case and further including a front permanently joined to the said part and projecting up therefrom, and the other section being a back section including a top and a back, and releasable retainers holding the lower edge portion of the back joined with the rear edge portion of the bottom and holding the upper edge portion of the front joined with the forward edge portion of the top.

2. A cooler case of the character described including, two separable unitary sections each generally L-shaped, one a main section including a lower horizontally disposed part forming the entire bottom of the case and a front joined to an edge of said part and projecting up therefrom, and the other a back section including a top and a back joined to an edge of the top and depending therefrom, and retainers releasably holding the lower edge portion of the back joined with the rear edge portion of the bottom and holding the upper edge portion of the front joined with the forward edge portion of the top, one retainer including a horizontally projecting part on the upper edge portion of the front and the other retainer including a vertically projecting part on the rear edge portion of the bottom.

3. A case of the character described including, two unitary sections each generally L-shaped, one a main section including a bottom and a front, and the other a back section including a top and a back, a flange projecting upwardly from the

rear edge of the bottom and holding the lower edge portion of the back joined with the rear edge portion of the bottom and a part holding the upper edge portion of the front joined with the forward edge portion of the top, and upwardly projecting flanges on the front and side edges of the bottom cooperating with the bottom and the flange projecting upward from the rear edge of the bottom forming a liquid catching tray in the bottom of the case.

4. A case of the character described including, two unitary sections each generally L-shaped, one a main section including a bottom and a front, and the other a back section including a top and a back, retainers holding the lower edge portion of the back joined with the rear edge portion of the bottom and holding the upper edge portion of the front joined with the forward edge portion of the top, one retainer including a horizontally projecting top flange on the upper edge portion of the front and the other retainer including a vertically projecting flange on the rear edge portion of the bottom, the front having a rearwardly projecting bottom flange on its lower edge engaging under the bottom and having rearwardly projecting side flanges on its side edges joined with the top flange and with the bottom flange.

5. A case of the character described including, two unitary sections each generally L-shaped, one a main section including a bottom and a front, and the other a back section including a top and a back, a rear flange on the bottom holding the lower edge portion of the back joined with the rear edge portion of the bottom and a top flange holding the upper edge portion of the front joined with the forward edge portion of the top, upwardly projecting flanges on the front and side edges of the bottom cooperating with the bottom and the rear flange forming a liquid catching tray in the bottom of the case, a rearwardly projecting bottom flange at the lower edge of the front and rearwardly projecting side flanges at the side edges of the front joined to the top flange and to the bottom flange.

6. A cooler case of the character described including, two separable unitary sections each generally L-shaped, one a main section including a part forming a complete bottom for the case and a front permanently joined to and projecting up from said part, and the other a back section including a top and a back permanently joined to the top and depending from an edge thereof, retainers releasably holding the lower edge portion of the back joined with the rear edge portion of the bottom and holding the upper edge portion of the front joined with the forward edge portion of the top, and sides carried by one section and releasably engaged with the other section.

7. A cooler case of the character described including, two separable unitary sections each generally L-shaped, one a main section including a part forming the entire bottom of the case and a front permanently joined to an edge of said part and projecting up therefrom, and the other a back section including a top and a back joined to an edge of the top and depending therefrom, retainers releasably holding the lower edge portion of the back joined with the rear edge portion of the bottom and holding the upper edge portion of the front joined with the forward edge portion of the top, and sides carried by the back section and releasably engaged with the other section.

8. In combination two separable unitary case sections, one a main section having an upwardly

opening tray shaped liquid carrying bottom and a vertically disposed front projecting upwardly at the forward edge of the bottom, and the other a back section including a back depending into the bottom and having a top with its forward edge portion releasably engaged with the upper edge portion of the front, and side sections carried by the back section in engagement with the bottom and the front.

9. In combination two separable unitary case sections, one a main section having an upwardly opening tray shaped liquid carrying bottom and a vertically disposed front projecting upwardly at the forward edge of the bottom, and the other a back section including a back depending into the bottom and having a top with its forward edge portion releasably engaged with the upper edge portion of the front, and side sections carried by the back section in engagement with the bottom and the front, the back of the back section and the side sections having air passages therethrough.
